BOILER

Emert J. Lattner, Cedar Rapids, Iowa

Application September 10, 1937, Serial No. 163,238

1 Claim. (Cl. 122—161)

This invention relates to boilers and particularly to the structure of the water jackets and casings for such boilers.

In all the conventional types of boilers, the hot gases pass through an area completely surrounded by water with the result that the gases in their travel contact surfaces not warmer than steam temperature, causing condensation of the gases and accumulation of carbon. Furthermore, the conventional types of boilers have not been compact and efficient and easy to assemble and disassemble.

I have found that in the process of heat transfer from gases to solids such as water jackets, boiler linings and the like, the efficiency of heat transfer is greater if a given volume of gases have passed over the surfaces at high velocity than if the same volume of gases pass over the surfaces at low velocities.

20 In the low velocity condition, it is probable that the efficiency of heat transfer is cut down because the layer of gas adjacent the water jacket transfers its heat and then acts as an insulating medium to prevent the heat transfer from gases at a distance from the surface.

It is, therefore, a general object of my invention to improve the efficiency of a boiler by cutting down the condensation of the gases and thereby materially reducing the accumulation of carbon.

Another object of my invention is to provide a means associated with and adjacent the water jacket which will attain a high temperature and act to transfer heat to the water jacket and reduce the accumulation of carbon.

Another object of my invention is to provide means for increasing the efficiency of heat transfer in a boiler.

Still another object of my invention is to provide means for selectively speeding up the velocity of heated gases as they pass over the water jacket of a boiler.

Other objects of my invention are to provide a new and improved boiler which shall attain high efficiency, which shall occupy relatively small space, which can readily be serviced and repaired and which is inexpensive to manufacture and maintain.

It is a feature of my invention that the velocity of gases is materially increased at the points where heat transfer to the water in the boiler takes place.

It is another feature of my invention that the inner lining of the casing adjacent the outer surface of the water jacket is comprised of a heat

absorbing and retaining material to thus maintain the temperature of the gases and prevent the accumulation of carbon.

Other and further features and objects of the invention will be more apparent to those skilled in the art upon a consideration of the accompanying drawing and following specification, wherein is disclosed a single embodiment of the invention, with the understanding, however, that such changes may be made therein as fall within the scope of the appended claim, without departing from the spirit of the invention.

In said drawing the figure is a view in perspective illustrating a boiler constructed according to one embodiment of my invention. A portion of the unit has been cut away to illustrate the parts thereof to better advantage.

While I have illustrated my invention as embodied in a unit suitable for use with an oil burner, it is quite obvious that the principles disclosed are applicable to a much wider range of structures.

The heat generating means may be an oil burner, a gas burner, a stoker, or hand fired furnace. While the boiler is shown in a vertical position, it is quite apparent that it could easily be arranged in a horizontal position as well.

Referring now to the drawing, the unit here shown is mounted upon a rectangular base 10 and employs a substantially rectangular ornamental 30 casing or cabinet 11 for housing the boiler. This housing is surmounted by a cap or cover 12 which may readily be removed to expose the interior of the unit.

The device here shown embodies an oil burner 35 13 which is bolted to a framework including the cover 14 and a supporting plate 16. The cover 14 is bolted to the front of the cabinet 11 by means of bolts 17. The plate 16 affords a support for the combustion chamber fire box 18 and, in the embodiment here shown, this fire box is a molded member frustoconical in form at the discharge end of the manifold of the oil burner as illustrated at 18a and cylindrical at the portion which is inside of the boiler, as illustrated at 18b. The 45 fire box 18 is insulated from the cover 14 by means of a layer of insulating material indicated at 19.

I preferably provide an insulating layer of low temperature insulation such as mineral wool at 50 21 inside of and adjacent to the wall of the casing 11. A high temperature insulation lining of material such as Super X or the like is employed inside of the low temperature insulation. This high temperature insulation is indicated at 22.

The water chamber of jacket is indicated generally at 23. The boiler is preferably constructed with an inner wall 23a, the cross sectional area of which is reduced from bottom to top, 5 for a purpose hereinafter set forth, and having a ring-like cap or dome 23b and a cylindrical outer wall 23c. The flame from the burner fills the fire box 18b and the interior of the boiler forms a secondary combustion chamber indicated generally at 24. The inner wall of the 10 boiler is constricted in order to increase the velocity of the gases as they pass over the water jacket to thereby secure the most rapid heat transfer.

15 The inner side of the high temperature insulation 22 is lined with a metal sheet, as indicated at 26, and the spacing of this inner lining with the cylindrical outer wall 23c of the boiler 23 is such that a further increase in 20 velocity of gases is obtained thereby obtaining a very rapid heat transfer from the gases to the shell of the water compartment 23 and to the inner lining 26. The heat absorbed by the metal inner lining is radiated to the shell of 25 the water compartment where the heat is given up to the water in the boiler. The metal sheet 26 takes on flame and gas temperatures, not only assisting by radiation to heat the water in the water jacket, but also to prevent condensation of the gases and deposit of carbon. Combustion of the gases is maintained by the lining 30 26 even after they leave the combustion chamber.

In order to insure even or distributed flow of 35 the heated gases over the inner and outer surfaces of the boiler, I provide a ring-like chamber 27 at the bottom of the outside wall of the boiler, the chamber 27 being preferably enlarged by leaving out a portion of the insulation 22. 40 The temperatures at this point are relatively much lower than in the combustion chamber and the high temperature insulation is not so necessary at this point, although of course, the insulation used must be sufficiently heat resistant 45 that it will not be injured by the highest temperature it is likely to meet. The chamber 27 extends entirely around the boiler, but is of course, reduced at the point 27a where the manifold enters the fire box. The gases pass 50 outwardly from the chamber 27 through the stack 28.

The device illustrated at 31 is an inspection conduit covered by the cap 32. The device illustrated at 33 is a thermostat having the heat responsive element 33a projecting into the chamber 34 above the boiler. The device illustrated at 35 is a water temperature indicating device which is connected with the interior of the boiler. Water is introduced into the boiler 60 through the conduit 36 and is discharged from the boiler through the conduit 37.

The entire unit is readily assembled and disassembled. The oil burner may be removed from the cover plate 14 merely by removing the bolts 65 38 by which it is secured to the cover 14. The

cover 14 and fire box 18 may be removed as a unit by unscrewing the bolts 17. The inspection conduit 31 is readily disassembled and can be readily removed by reason of the telescopic structure of the conduit. The water temperature indicator 34 and thermostat 33 are also readily removable. The boiler may be removed from the unit by taking off the top 12 and lifting the entire boiler from inside the cabinet.

In operation the greater part of the fuel 10 burns in the combustion chamber or fire box 18 and secondary combustion takes place in the chamber 24 above the fire box. The gases pass upwardly, as indicated by arrows, their rate 15 of flow being increased by the constriction in the inner wall of the boiler. The heated gases pass outward over the crown or cap of the boiler and down the outside wall of the boiler. The gases tend to spread evenly over the entire outside wall of the boiler by reason of the constriction afforded by the wall 26 and, after they have passed over the outer wall of the boiler, they pass around the boiler in the channel 27 and out through the stack 28. The gases have given up the greater portion of their heat by 25 the time they reach the stack 28 and this heat is given up at the proper points with reference to the boiler, that is, at the inner and outer walls thereof. Both the inner and outer walls 30 of the boiler are used. Space is conserved by passing the gases upwardly and then downwardly over the outside of the boiler.

It is apparent that modifications of my invention may be made by those skilled in the art. Such modifications may be made without departing from the spirit and scope of my invention as set forth in the appended claim.

I claim as my invention:

In a boiler, an outer casing of heat insulating material, an inner casing also of heat insulating material suspended from the inner wall of the outer casing at the upper portion thereof to thus afford a channel of greater area at the lower inner wall than at the upper inner wall, and a cylindrical water chamber adapted 40 to fit within the casing and to rest on the floor of the casing, the water chamber having a cylindrical outer wall and a curved ring-like cap, and having an inner wall the cross section of which is reduced from bottom to top, whereby 45 gases passing upwardly through the inner passageway thus formed increase in velocity as they flow upward, the spacing between the cylindrical portion of the water chamber and the double thickness wall of the casing being of 50 relatively smaller area than that of the inner passageway, whereby the velocity of gases is still further speeded up and the single thickness of the outer casing at the lower portion thereof 55 affording an enlarged passageway or equalizing chamber, whereby gases may pass around the lower portion of the water chamber in substantially horizontal direction to a stack opening.
